PARAFFIN SCRAPER

Randolph Bryant, Jr., Houston, Tex., assignor to Gulf Oil Corporation, Pittsburgh, Pa., a corporation of Pennsylvania

Application August 6, 1954, Serial No. 448,308

4 Claims. (Cl. 166—173)

This invention relates to a paraffin scraper especially useful in removing the accumulation of paraffin deposited on the interior surface of flow pipe in flowing and gas-lift oil wells.

In oil wells it has been found that where the effluent contains paraffin, paraffin is deposited on the inner surface of the flow pipe so that removal of the paraffin is essential in order to maintain normal production of the well. Various solutions for this problem have been proposed, such as the use of scrapers mechanically operated from the surface, solvents, and scrapers operated by means of the force of gravity and the energy of the oil flowing in the flow pipe. The present invention is concerned with a scraper of the last-named type. The scraper of the invention has the advantages of being uncomplicated in design and economical to manufacture and repair.

The details of construction and operation of the scraper are more fully described hereinafter, reference being made to the accompanying drawings which constitute a part hereof, wherein like numerals refer to like parts throughout and in which:

Figure 1 is a longitudinal sectional view of a flow pipe showing the lower part of the scraper therein in longitudinal cross section;

Figure 2 is a longitudinal sectional view of a flow pipe showing the center part of the embodiment of the scraper shown in Figure 1 in longitudinal cross section.

Figure 3 is a longitudinal sectional view of the upper part of the embodiment of the scraper shown in Figures 1 and 2 in longitudinal cross section.

Figure 4 is a longitudinal sectional view of the upper part of another embodiment of the invention in longitudinal cross section.

Figure 5 is a longitudinal sectional view of a flow pipe containing the upper part of the scraper shown in longitudinal cross section to illustrate a different structure for controlling the reciprocating motion of the parts of the scraper.

Figure 6 is a cross section of the scraper taken along line VI—VI of Figure 5.

Figure 7 is a longitudinal sectional view of a flow pipe containing the scraper therein and showing the upper and lower limits within which the scraper is intended to operate.

Referring to Figures 1, 2 and 3 in detail, wherein for the purpose of illustration is disclosed a preferred embodiment of my invention, there is shown an oil producing tubing or flow pipe 10 in which is placed the paraffin scraper which is designated generally by the numeral 11. A hollow cylinder 12 is placed within the oil producing tubing or flow pipe between upper and lower stops (Figure 7) arranged at the upper and lower limits between which it is desired to remove paraffin deposited in the flow pipe. Stops 58 and 59, consisting of horizontal bars welded or fastened by other suitable means across the inside diameter of the flow pipe 10, are located at the upper and lower limits within which the scraper is intended to operate. It will be understood that any other suitable

2

type of stops which would not obstruct the fluid flow in flow pipe 10 could be employed. The upper stop may be fixed in an upper section of the flow pipe to permit the insertion and removal of the scraper by disconnecting the various sections of the flow pipe. Attached to and forming a part of the lower end of cylinder 12 is a circular blade 13 of a size such that there is a slight clearance between its periphery and the inner surface of the flow pipe.

10 Within the hollow cylinder 12 is a rod 14 such as a conventional sucker rod, of substantially smaller diameter than the inner diameter of the cylinder, and centrally positioned at its upper end within cylinder 12 by arcuate positioning springs 15. These springs are fitted into suitable key slots 16 in rod 14 which are of such length as to permit movement of the lower end of springs 15 when under compression. The springs 15 are compressed in passing over an indented annular neck 17 which protrudes from the inner surface of cylinder 12. The neck 17 serves as 15 a detent for the springs 15, to maintain the relative positions of cylinder 12 and rod 14 during normal operation by positioning rod 14 centrally with relation to cylinder 12 and by preventing vertical slipping. Valve element 18 has an integral portion of its structure extending downward below the valve structure forming an extension 23 which effectively operates as an extension of rod 14. Extension 23 is the lowermost portion of scraper 11 in all 20 positions, and is that portion of the scraper which strikes the lower stop 59 when such contact is made. However, upon striking the lower stop for the downward motion of the scraper, the impact of arrested motion is sufficient to cause positioning springs 15 to compress and pass over annular neck 17. Thereafter the positioning springs resume their non-slipping function until the upper 25 end of rod 14 makes contact with the upper stop, whereby springs 15 are again caused to compress and pass over the annular neck. Three such springs will normally be used, each of which is separated from the others by 120° of arc.

30 40 A cup-shaped valve element 18 surrounds and is attached to the lower part of rod 14 by threaded means 19. This member functions as one element of the valve to be described. The upwardly extending rim 20 of valve element 18 fits slidably within the lower end 22 of cylinder 12. Rim 20 contains ports 21, shown as U-shaped slots, through which oil may flow when these ports are not covered by the lower end 22 of cylinder 12. An extension 23 of valve element 18 extends below the lower end 22 of cylinder 12 and is the part of the scraper to make contact 35 when the scraper strikes the lower stop.

40 50 Two blocks 24 and 24a are positioned at right angles to one another in closely fitting slots in rod 14 and extend beyond the rod on both sides. The extensions of block 24 shown at 25 fit slidably within slots 26 in cylinder 12. Slots 26 are longer than block 24 the excess length being the distance of relative longitudinal movement between rod 14 and cylinder 12 required for covering and uncovering ports 21 in valve element 18. The parts 27 of extensions 25 extend through and beyond the slots in the walls of cylinder 12 and function as an aid in positioning the scraper 11 centrally within the flow pipe 10. The parts 27 and 27a of blocks 24 and 24a extend very close to the inner surface of flow pipe 10 so that if and when scraper 11 deviates from a 55 60 concentric position within the flow pipe the extended portions 27 and 27a of blocks 24 and 24a will be the first part or parts of the scraper to touch the inner surface of the flow pipe and will function as rails or skids to direct and straighten the motion of the scraper until it is once more moving parallel to the inner surface of the flow pipe. It will be understood that although parts 27 and 27a extend close to the inner surface of the flow pipe 65 70

they are not in contact except upon deviation of the scraper from motion parallel to the inner surface of the flow pipe. A layer of deposited paraffin coats the inner surface of the flow pipe providing a lubricating means. If some clearance were not allowed between parts 27 and 27a and the inner wall of the flow pipe the scraper might fit too snugly and the presence of paraffin might cause the scraper to jam in the flow pipe. It will be understood that block 24a is provided with extensions similar to 25 and 27 which function in slots 26a in identical manner to extensions 25 and 27 in slots 26. As shown, steel snap rings 28 and 28a, positioned in grooves 29 and 29a in cylinder 12, hold blocks 24 and 24a in position.

At the upper end of rod 14 and attached thereto by threaded joint 32 is a fishing neck 33 with a larger head portion 34 suitable for handling with a fishing tool for the purpose of placing the scraper 11 in or removing it from the flow pipe 10. The neck 33 and head 34 attached to rod 14 extend beyond the upper end of cylinder 12 in order to make contact with the upper stop and in order to be easily accessible to a fishing tool.

In the operation of the device shown in Figures 1, 2 and 3, the paraffin scraper 11 is placed in the flow pipe 10 with rod 14 at its lowermost position with relation to cylinder 12 as shown in Figure 1. In this position the springs 15 are below annular neck 17, see Figure 3, positioning blocks 24 and 24a are at their lowermost position in slots 26 and 26a provided in cylinder 12, see Figure 2, and ports 21 in the upwardly extending rim 20 of valve element 18 are uncovered as shown in Figure 1, permitting the upward flow of oil in the flow pipe, through ports 21 and upward through the interior of cylinder 12. In this position the scraper falls by its weight and circular blade 13 scrapes off the accumulation of paraffin from the interior surface of flow pipe 10. The paraffin thus detached is washed through ports 21, upward through cylinder 12 and on up the flow pipe by the upward flow of fluid. This flushing action constitutes an important advantage of the invention as the removed paraffin is not deposited in the relatively dead space outside of the body of the scraper and therefore cannot accumulate on the outside of the tool and cause it to stick in the flow pipe. When the falling scraper 11 reaches the lower stop, 59, the extension 23 of valve element 18 attached to the lower end of rod 14 strikes the stop with considerable impact causing cylinder 12 to slide downward with relation to rod 14. In this position the lower end 22 of cylinder 12 covers ports 21 thus preventing the flow of oil upward through flow pipe 10. The distance traveled by cylinder 12 with relation to rod 14 after the scraper strikes the upper and lower stops is limited by the length of slots 26 and 26a in cylinder 12 in which blocks 24 and 24a are guided. With ports 21 in valve element 18 closed, the free upward flow of oil in the flow pipe is substantially obstructed and sealed off so that scraper 11 is forced upward by the flow of oil in the flow pipe until head 34 attached to rod 14 strikes the upper stop 58. The sudden impact arresting upward movement of rod 14 causes cylinder 12 to travel upward with relation to the rod 14 and with relation to valve element 18 thereon thus uncovering ports 21 and permitting the free flow of oil through these ports and upward through cylinder 12. Upward pressure on the scraper being thereby relieved, the scraper falls in flow pipe 10 by its weight repeating the operation described.

It will be understood that the embodiment shown in Figures 1, 2 and 3 can be modified in certain respects without departing from the scope of the invention. For example, in a case where it is desired to accomplish scraping of the flow pipe during the upward movement of the scraper as well as during its downward movement, the scraper may be provided with another scraper blade 13a, which is similar but not identical to blade 13, and is attached adjacent the upper end 42 of cylinder 12. Such a blade is shown in Figure 4. The blade shown there is

cylindrical in shape and attached to rod 14 by two or more rigid arms 43 at a point above the upper end 42 of cylinder 12, an annular space being provided between the lower end of blade 13a and the upper end 42 of cylinder 12 as shown in Figure 4.

Referring to Figure 4, there is disclosed another embodiment of the invention in which a sleeve valve is disposed in the upper end of the cylinder 12. It will be understood that this valve would normally be employed in place of the valve shown in Figure 1. In this embodiment there is attached to a shoulder 37 on rod 14, a cylindrical valve element 38 having ports 39. These ports are disposed at intervals around the circumference of the valve element 38. The upper end of cylinder 12 in this embodiment is provided with corresponding ports 41. The operation of the scraper involves the downward movement of cylinder 12 when the scraper strikes the lower stop in the flow pipe. On this impact, the imperforate section 42 of cylinder 12 slides downwardly to cover ports 39. As a result, the flow of oil through the scraper is prevented and the scraper is caused to move upwardly by the upward flow of fluid in the well until it strikes the upper stop. When this occurs the cylinder 12 is forced upwardly with relation to rod 14 for a distance limited by extensions 25 and 25a of rod 14 moving in slots 26 and 26a. At this point in the movement of the scraper in the flow pipe, the relative longitudinal positions of the valve element 38 and cylinder 12 will be as shown in Figure 4. With ports 39 and 41, coinciding, the flow of oil proceeds upward through cylinder 12 and out through valve ports 39 and 41, upward in flow pipe 10 outside the upper end 42 of cylinder 12, through the annular space between the upper end 42 of cylinder 12 and the lower end of the upper blade 13a, upward through the interior of cylindrical blade 13a and on upward in flow pipe 10. As the upward flow of oil is unobstructed the scraper is caused by gravity to fall downwardly in the flow pipe, counter to the fluid flow, until the lower stop is reached.

When a valve is used at the upper end of cylinder 12, as above described, it is advantageous to provide short cylindrical sleeves 57 and 57a attached below positioning blocks 24 and 24a within or outside of cylinder 12 in order to cover the open portions of slots 26 and 26a during the upward travel of the scraper so that the hydraulic force provided by the upward flow of fluid elevating the scraper, is not lost by leakage through the open portions of the slots 26 and 26a, as shown in Figures 1 and 2.

A scraper blade attached adjacent the upper end of cylinder 12 will normally be used only in conjunction with a scraper blade attached adjacent the lower end of the cylinder. A scraper blade attached adjacent the lower end of cylinder 12 in this case is important, because after the scraper strikes the lower stop which causes the valve mechanism of the scraper to close, the circumference of the scraper blade attached adjacent the lower end of the cylinder forms a seal between the scraper 11 and the inside of flow pipe 10, thus subjecting the scraper to the maximum amount of the hydraulic force exerted by the upward flow of oil in the flow pipe which will carry the scraper upward with the fluid flow until it reaches and strikes the upper stop, which in turn causes the valve mechanism of the scraper to open, again placing the scraper in position to travel downward and repeat the operation described.

Referring now to Figures 5 and 6 there is shown a variation of the invention providing a somewhat different structure as a means for controlling the longitudinal reciprocating movement of rod 14 and cylinder 12, thereby respectively opening and closing the valve means of the scraper as above described. In this embodiment of the invention the new structure described is a variation of structure in place of positioning blocks 24 and 24a, thus eliminating blocks 24 and 24a, slots 26

and 26a, snap rings 29 and 29a, and grooves 28 and 28a. This modification will simplify the machining necessary to manufacture the scraper, provide a larger bearing surface for impact loads when the tool hits the stops, and simplify the assembly and disassembly of the tool.

At the upper end of cylinder 12 attached by threaded means 44 is an extension 45 of cylinder 12 with a reduced diameter as at 46. Rod 14 extends within the cylinder extension 45 and is joined by threaded means 47 to block 48. An extension 14a of rod 14 is attached to block 48 by threaded means 49. The extension of the rod 14a continues upward to attach to the neck 33a and head 34a by threaded means 32a. Block 48 extends horizontally beyond rod 14 and 14a on both sides, fitting slidably within slots 51 provided in extension 45 for the accommodation of such block. At the upper end of slots 51, rigidly attached to extension 45 of cylinder 12, is a solid cylindrical member 50, having a central channel 52 which extends therethrough, and in which rod 14a fits slidably. The upper surface 53 of cylindrical member 50 and the lower surface 54 of said cylindrical member serve as bearing surfaces to absorb the impact loads when the lower surface 55 of neck 33a and the upper surface 56 of block 48 respectively strike the upper and lower surfaces of member 50.

When the scraper strikes the lower stop 59 in flow pipe 10, the impact forces cylinder 12 with its extension 45 and attached cylindrical member 50 downward with respect to rods 14 and 14a and block 48. This downward movement is stopped by the lower surface 54 of cylindrical member 50 striking the upper surface 56 of block 48. The described downward movement of cylinder 12 with relation to rod 14 covers ports 21 in the upwardly extending rim 20 of the valve element 18 attached to rod 14 as shown in Fig. 1, thereby closing ports 21 and forcing scraper 11 upwardly by the flow of fluid in flow pipe 10, as previously described.

When the scraper strikes the upper stop 58 in flow pipe 10, the impact forces cylinder 12 with its extension 45 and attached cylindrical member 50 upward with respect to rods 14 and 14a. This upward movement is stopped by the lower surface 55 of neck 33a, striking the upper surface 53 of cylindrical member 50. The upward movement of cylinder 12 with relation to rod 14 uncovers ports 21 in the upwardly extending rim 20 of valve element 18 attached to rod 14 as shown in Fig. 1, thereby opening the ports 21 and permitting the free flow of fluid upward in flow pipe 10 through the interior of scraper 11 so that the scraper is released from the elevating force of the fluid and is free to fall by its own weight, counter to the fluid flow in flow pipe 10, and in so doing to scrape the accumulation of paraffin from the interior surface of flow pipe 10 by action of scraper blade 13. Slots 51 are of sufficient length so that when block 48 is in its lowermost position with relation to cylindrical member 50, a portion of the slots 51 is below block 48 and remain open, as is shown in Fig. 5, so that the upward passage of fluid within cylinder extension 45 is unobstructed.

In this embodiment of the invention, cylindrical member 50 acts as the stop to control the reciprocal relative movement of rod 14 and cylinder 12, and the length of rod 14a determines the extent of relative motion. The use of cylindrical member 50 is also advantageous in that it provides larger bearing surfaces to absorb the impact loads when the upper surface 56 of block 48 and the lower surface 55 of neck 33a strike its lower and upper surfaces respectively.

Obviously many modifications and variations of the invention, as hereinbefore set forth, may be made without departing from the spirit and scope thereof; therefore only such limitations should be imposed as are indicated in the appended claims.

I claim:

1. A paraffin scraper adapted for free longitudinal movement within an oil well flow pipe provided with upper and lower stops in the path of said scraper, said scraper comprising a hollow cylinder having a longitudinal slot intermediate the ends thereof, a circular scraper blade attached adjacent an end of said cylinder and projecting outwardly therefrom, a rod positioned axially within said cylinder, said rod having a lateral extension intermediate the ends thereof fitting slidably within said slot in said cylinder, said slot and said extension cooperating to limit the relative longitudinal movement of said cylinder and said rod when said rod strikes a stop, a cup shaped sleeve valve element having ports therein mounted on said rod adjacent an end thereof, said sleeve valve element fitting slidably within an end of said cylinder, whereby the ports in said sleeve valve element are adapted to be alternately covered and uncovered by the relative longitudinal movement of said cylinder and said rod.

2. A paraffin scraper adapted for free longitudinal movement within an oil well flow pipe provided with upper and lower stops in the path of said scraper, said scraper comprising a hollow cylinder having at least two longitudinal slots intermediate the ends thereof, a circular scraper blade attached adjacent an end of said cylinder and projecting outwardly therefrom, a rod centrally positioned axially within and extending longitudinally beyond the ends of said cylinder, said rod having at least two lateral extensions intermediate the ends thereof fitting slidably within said slots in said cylinder, said extensions and said slots cooperating to limit the relative longitudinal movement of said cylinder and said rod when said rod strikes a stop, a cup shaped sleeve valve element having ports therein mounted on said rod adjacent an end thereof, said sleeve valve element fitting slidably within an end of said cylinder, whereby the ports in said sleeve valve element are adapted to be alternately covered and uncovered by the relative longitudinal movement of said cylinder and said rod.

3. A paraffin scraper adapted for free longitudinal movement within an oil well flow pipe provided with upper and lower stops in the path of said scraper, said scraper comprising a hollow cylinder having a longitudinal slot intermediate the ends thereof, a circular scraper blade attached adjacent an end of said cylinder and projecting outwardly therefrom, a rod positioned axially within and extending longitudinally beyond the ends of said cylinder, said rod having a lateral extension intermediate the ends thereof fitting slidably within said slot in said cylinder, said extension and said slot cooperating to limit the relative longitudinal movement of said cylinder and said rod when said rod strikes a stop, a cup shaped sleeve valve element having ports therein mounted on said rod adjacent an end thereof, said sleeve valve element fitting slidably within an end of said cylinder, whereby the ports in said sleeve valve element are adapted to be alternately covered and uncovered by the relative longitudinal movement of said cylinder and said rod, arcuate positioning springs carried by said rod and contacting said cylinder, an inwardly extending annular neck on said cylinder positioned substantially mid-way between the extreme limits of movement of said springs with respect to said cylinder, whereby said springs position said rod centrally within said cylinder and cooperate with said neck to maintain said rod in either extreme longitudinal position with respect to said cylinder.

4. A paraffin scraper adapted for free longitudinal movement within an oil well flow pipe, said scraper comprising a hollow cylinder provided with longitudinal slots adjacent the upper end thereof, a rod axially positioned within and extending longitudinally beyond the ends of said hollow cylinder and adapted for relative longitudinal movement with respect to said hollow cylinder, a solid cylindrical member integrally attached to the upper end

of said hollow cylinder above said slots, said solid cylindrical member being provided with a longitudinal channel and said rod extending through and slidably fitting in said longitudinal channel, an enlarged head portion at the upper end of said rod above said solid cylindrical member, a lateral extension of said rod fitting slidably within said slots within said hollow cylinder, a circular scraper blade attached to the lower end of said hollow cylinder and projecting outwardly therefrom, and valve means comprising a slotted cup-shaped member attached

10 to the lower end of said rod and fitting slidably within the lower end of said hollow cylinder.
